(57) **CLAIM**

The ornamental design for a toilet bowl pet water dish, as shown and described.

DESCRIPTION

FIG. 1 is an isometric view of a toilet bowl pet water dish with the seat portion in a lowered position, wherein the broken lines illustrate hinges in the environment;

FIG. 2 is a front view of FIG. 1;

FIG. 3 is rear view FIG. 1;

FIG. 4 is a left-hand side view FIG. 1;

FIG. 5 is a right-hand side view FIG. 1;

FIG. 6 is a top view FIG. 1;

FIG. 7 is a bottom view FIG. 1;

FIG. 8 is an isometric view the toilet bowl pet water dish with the seat in a raised position, wherein the broken lines illustrate hinges in the environment;

FIG. 9 is a front view FIG. 8;

FIG. 10 is rear view FIG. 8;

FIG. 11 is a left-hand side view FIG. 8;

FIG. 12 is a right-hand side view FIG. 8;

FIG. 13 is a top view FIG. 8; and,

FIG. 14 is a bottom view FIG. 8.

The broken lines shown in the drawings illustrate the environment of the article and form no part of the claimed design.
